UNITED STATES PATENT OFFICE.

GUSTAVE O. DEGENER, OF BROOKLYN, NEW YORK, ASSIGNOR TO ROYAL TYPEWRITER COMPANY, INC., OF NEW YORK, N. Y., A CORPORATION OF NEW YORK.

ADDING ATTACHMENT FOR TYPEWRITING MACHINES.

Application filed March 9, 1925. Serial No. 14,315.

My invention relates primarily to an adding attachment for typewriting machines of the general character shown in my prior application No. 736,896 filed Sept. 10, 1924.

5 Portions of the mechanism are the same as shown in my prior case, and will not be described in entire detail herein.

The invention is embodied in an attachment which can be readily attached to and 10 detached from the frame of a typewriting machine, and requires substantially no change in the construction of the typewriting machine. The adding mechanism is operated only when the carriage of the typewriter enters the adding zone and may be 15 easily disconnected from the carriage so that writing may be performed in the adding zone without operating the adding attachment. It is located at one side of the 20 typewriting machine and does not obstruct the line of sight to the paper nor interfere in any way with the usual operation of the typewriting instrumentalities.

While it is illustrated as applied to the 25 well-known Royal Standard machine, it is to be understood that the attachment may be applied to any of the standard commercial machines, only minor changes in the 30 connections being required and none in the structure of the adding mechanism itself.

This computing attachment is designed primarily for billing purposes, and can be employed wherever this class of work is to be performed. In making out such bills or 35 statements, the various items are written each with date, name of article, etc., and the carriage is then moved preferably by tabulating mechanism to the first computing zone where the separate amounts are written, 40 one under the other. At this time these amounts are set up in the column totalizer, the figures of which at any time will show the sum of the detail items written.

When the bill is finished, it is desired to 45 write the total in a second column, and the carriage is moved to bring the paper into position to write the sum in this column and also bring the carriage into the second computing zone. The sum is then written, being 50 copied from the figures appearing in the column totalizer and the carriage is returned to initial position to begin writing of the succeeding bill.

In computing machines previously em- 55 ployed for this class of work, there have

been numerous chances of error, which have caused objections thereto. It has been ordinarily necessary to move a lever to subtract position upon writing the total, at which time the column totalizer is usually cleared and at the same time the sum is set up in the grand totalizer. It frequently happens that the operator forgets to move the lever to subtract position, which results in the amounts appearing in both totalizers being 60 wrong.

In my previous application I overcome this objection to a considerable extent by rendering it impossible to return the carriage to position to begin a new line of writing until the total has been correctly copied and the column register cleared. This mechanism, while overcoming any objections to prior constructions, nevertheless did not prevent the error but merely rendered it necessary to correct the same before continuing 75 with the succeeding bill.

An object of my present invention is to prevent the occurrence of any such errors. Accordingly the mechanism comprises means 80 whereby when the carriage is moved into the second computing zone and the general totalizer brought into register with the master wheel, it is impossible to write any figures except those appearing in the column 85 register and is impossible to write these figures in any except the correct denominational positions. This construction precludes the possibility of an error arising when the total is written.

The second important feature of my invention relates to means for clearing the column totalizer after the sum has been written and a number set up in the grand totalizer. This comprises means whereby 90 after the carriage has been moved into the second computing zone and a number set up in the grand totalizer, the return movement of the carriage itself will automatically clear the column totalizer without any attention upon the operator's part. The writing of a total and the subsequent clearing of the totalizer, therefore, takes place without the movement of any lever to subtract position or without the actuation of 95 any special means whatever for the purpose of clearing the column totalizer.

A further feature of the invention relates to the indicator which will show at all times what digit has been added and in which de- 100 105 110

nominational position this digit stands. This is important because it frequently happens that an operator will depress a key with insufficient force to print, but enough to actuate the adding mechanism and set up the digit in the register. Even if the operator realizes the possibility of an incorrect operation, it is unnecessary to pause and make a mental computation to see whether the number not printed has been entered into the column totalizer. The indicating means which is embodied in this invention shows as each key is struck whether or not it is printed whether or not the digit has been entered into the totalizer in the proper position. This obviates the necessity of full stroke mechanism for the downward movement of the keys and enables the operator to know what amount was entered in the register by the last key operated.

Another feature of the invention consists in the provision of a spring which draws the traveling registers from right to left independent of the connection between the register and the typewriter carriage. This is for the purpose of relieving the step by step movement of the typewriter carriage from the added resistance caused by the connection thereto of the adding mechanism. It has been found preferable to throw the increased strain upon the return movement of the typewriter carriage rather than upon the step by step movement thereof. Accordingly means is provided for holding the register in its extreme right hand position during the time that it is automatically disconnected from the typewriter carriage.

Another object of the invention is the provision of a modified construction of error check mechanism whereby whenever an incorrect key is struck while the grand totalizer is in the computing zone the depression of the key is not prevented but its return movement is stopped. The operator is therefore notified that an error has been made and can correct the same before writing further.

In both cases the complete operation of the key is prevented but in one form the error check mechanism operates to prevent the complete depression while in the other form it operates to prevent a complete return movement.

Another object of the invention is to provide special means for properly aligning the various register wheels especially after an extended automatic carrying operation. Whenever an extended carrying operation takes place a spiral lag usually develops from wheel to wheel, due to the play allowed in each set of gears; therefore, when a large number of wheels are in the automatic carrying train, the wheel of the highest denomination might not be turned sufficiently to be in its proper position. Means is therefore

provided for correctly aligning certain of the carrying wheels or other elements of the train of gearing in order to prevent the possibility of any such erroneous operation.

Various other objects of the invention will be apparent from the following detailed description and the appended claims.

In the drawings:

Figure 1 is a top plan view of the attachment in position on a typewriting machine, conventionally illustrated, and also shows a sample of the character of work that the invention is particularly adapted to perform.

Figure 2 is a front view of a detail, showing the lock sectors for preventing depression of the wrong key when writing the total.

Figure 3 is a partial fore and aft section with parts in elevation taken on the line 3-3 of Figure 5.

Figure 4 is a front view of a portion of the mechanism shown in Figure 3.

Figure 5 is a top plan view with parts in section of the attachment with the traveling register and actuating parts removed.

Figure 6 is a fore and aft vertical section taken on the line 6-6 of Figure 5.

Figure 7 is a rear view taken at an angle of about 45° showing the mechanism for bringing the register to home position and retaining it therein when disconnected from the carriage.

Figure 8 is a perspective view of one of the auxiliary indicators.

Figure 9 is a fore and aft section showing the register and train of connections for actuating the same.

Figure 10 is a detail view of the master wheel shaft, together with the cams for locking and unlocking the carrying wheels.

Figure 11 is a longitudinal section of a modification of the error check mechanism showing only such parts as are necessary to disclose wherein the construction differs from the first form.

Figure 12 is a top plan view of a portion of this modification corresponding in general to Figure 5.

Figure 13 is a transverse section on the line 13-13 of Figure 12 looking in the direction of the arrows.

Figure 14 is a side elevation with parts in section of the special alining mechanism.

Figure 15 is a front view of the same.

The invention has been illustrated in connection with a Royal Standard machine although it is capable of application to any of the various commercial typewriters. The typewriting mechanism itself has been illustrated only conventionally since this precise structure forms no part of the invention. There is shown a machine frame A, a carriage B supporting a platen C, type bar mechanism D, ribbon mechanism E, and a

keyboard F provided with numeral keys G having levers G'. All of these parts may be of any suitable or desired construction.

The attachment proper comprises a casing 1, the front portion of which is narrower than the rear portion, said casing being formed by a left hand side plate 2, an intermediate plate 3 which forms the right side of the front narrow portion, and a right hand side plate 4. These plates are tied together (see Figure 6) by tie rods 5 and 6, by a rear transverse member 7 having shelves 8 and 9, by a front transverse member 10 having a shelf 11, and by rods 12 and 13 upon which the register travels. There is also provided a top and front plate 14 and bottom plate 15. At the top rear portion the register frame is attached to the typewriter frame by screws 16 and 17 (see Fig. 1). At the front there is attached to the bottom plate 15 a trough shaped plate member 18 (see Figs. 1, 5 and 6) which extends under the keyboard of a typewriting machine and is fastened thereto by screws 19. It is, therefore, apparent that the attachment may be removed by merely removing screws 16, 17 and 19 and disconnecting the numeral key levers from the mechanism operated thereby.

Suitably supported in the trough of the plate 18 and underlying a portion of the typewriter keyboard F is a series of ten rock shafts 20 positioned in vertical pairs. Each rock shaft is provided at its left end with a rearwardly extending crank arm 21 connected by a link 22 to the corresponding key lever G'. An upwardly extending crank arm 23 is attached to the right hand end of each rock shaft and this crank arm is pivoted at its upper end to a sliding bar 24. It will be noted that the crank arms 21 and 23 are so arranged that the proper movement will be given to the bars 24 notwithstanding the fact that some of the rock shafts 20 are arranged farther from the key stems G' than the others.

At their rear ends the bars 24 rest on a rod 25 (see Figure 6) and are guided by a comb 26 formed of a piece of sheet metal bent to substantially surround the rod 25 and provided with an upwardly extending slotted edge portion. The transverse member 10 supports a sheet metal member 27 which is slotted to form a series of fingers bent at their lower end to form a substantial cylinder 28, (see Figures 5 and 6). Balls 29 are placed in the cylinder and held by stops at the ends thereof so that there is just enough play to permit the passage of a depending projection 30 on the bars 24 through its corresponding slot. When one key is depressed and its connected bar 24 moved until the projection 30 passes between two of the series of balls 29, it is impossible to depress a second key lever at this time.

The extreme rear end of the arm 24 has a lug 31 which contacts with the rod 25 to limit the return movement of the bar and also has an additional function to be described later. The rear portion of the bar 24 is provided on its upper surface with rock teeth 32 which actuate a train of mechanism about to be described.

The train of mechanism actuated by the bar 24 for setting up in the register the digit corresponding to the key depressed is similar in its main features to that of my prior application and will be described mainly with reference to Figure 9.

There are provided a series of cam gears 33 mounted on a cam shaft 34, each of which gears has teeth 35 adapted to mesh with the teeth 32 of the corresponding bar 24. Each of these gears also has a series of teeth 36 varying in number according to the denomination of the key lever adapted to actuate the same. On one side of each cam gear 33 are positioned cams 37 and 38 for a purpose hereinafter described.

Located above the cam gears is a shaft 39 on which slides and rotates a sleeve 40 carrying an elongated pinion near one end and a series of unit pinions 41, as in my prior application. The unit pinions are normally out of position to mesh with the teeth 35 of the cam gears, but are moved into alignment therewith by the first portion of the movement of the cam gear. This is brought about in the following manner.

Mounted on the shelf 8 by means of a screw 42 is a plate 43 having one end bent to form an eye 44 in which rotates a stud 45 supporting a pawl member 46. A link 47 connects the member 46 with an arm 48 of a member 49 having a U shaped bearing on a pivot 50 which is mounted at its upper end in the plate 43 and at its lower end in an ear 51 offset from said plate 43. A member 49 has a forwardly extending arm 52 terminating in a rounded end 53 which engages between the elongated pinion and the adjacent unit pinion 41. Obviously when the pawl member 46 is rocked the member 49 will be rocked about pivot 50 and the sleeve 40 will be moved lengthwise to bring the unit pinions into position to mesh with whichever of the cam gears 33 is operated. The rocking movement is transmitted to the pawl member 46 in the following manner.

A sheet metal member 53' has one edge wrapped around a rod 54 supported in frame members 2 and 3. The other edge 55 occupies the position shown in Figure 9 and is engaged by the cam 38 on any one of the cam gears 33 when it is rotated. This rod 54 has a crank arm 56 which carries a roller 57 at its end and this roller is adapted to engage the lower rearwardly projecting end 58 of the pawl member 46. Whenever a key is depressed, a cam gear 33 is operated

and the cam 38 engages the lip or edge 55 and rotates the member 53 in clockwise direction and through the engagement of the roller 57 with the end 58 of the pawl member 46 will rock said pawl member. As soon as the cam 38 passes beyond the lip or edge 55, the pawl member 46 is returned to normal position by a spring 59 attached at one end to the pawl member and at its other end to an upturned lug 60 on the plate 43.

The cam 38 has notches 61 in its edge facing in one direction. On the down stroke of the key when the member 53 is rocked in clockwise direction, there will be no locking engagement between the edge 55 and the notches 61. On the up stroke of the key, however, the opposite edge of the cam member 38 comes into contact with the lip 55 and rocks the member 53 in counter-clockwise direction. During this movement the engagement of the lip 55 with notches 61 will act to prevent a second depression of the same key until it has returned fully to normal position. In effect this is a full stroke mechanism which acts only during the return movement of the keys. During this counter-clockwise movement of the member 53, the roller 57 engages the end of a lever 62 which is pivoted at 63 and normally drawn by a spring 64 against a stop 65. This operates to return the member 53 to normal position after the depressed key has returned to its normal position. Underlying the roller 57 but in a different vertical plane from the lower end 58 of the lever 46 is the end of a disconnect lever 66 which when operated engages said roller 57 and thereby moves the member 53 in counter-clockwise direction and by moving the edge 55 out of position to be engaged by the cam 38 allows the cam gears to be operated idly without operating the computing mechanism. This construction is substantially that of my prior application and is used for disconnecting the computing mechanism when the carriage is out of the computing zone. The parts are returned to normal position after this actuation by the lever 62 above described.

It may be noted at this point that the pawl member 46 has a rearward extension 67 adapted to overlie one of a plurality of fixed projections 68 when the carriage is in the position for writing the comma or the period in a number to be written. This prevents the operation of the pawl member 46 when the carriage stands in such positions and by locking the whole trains of connections prevents the depression of the numeral keys at these points.

A plate 69 fixed to the shelf 11 has one edge divided into fingers which are turned at their ends to form eyes in which is supported a shaft 70 upon which are pivoted

a series of unit pinion pawls 71. The tail of each of these pawls is weighted to hold the nose thereof out of engagement with its corresponding unit pinion 41. The pawl is provided with a projection 72 which is engaged by the cam 37 upon the rotation of the cam gear 33 to move the pawl 71 into engagement with the corresponding unit pinion.

The unit pinion 41 when moved by the actuated cam gear transmits motion through gears 73 and 74 to master wheel 75 which is normally held by the nose of the pawl member 46. However, at this time it will be apparent from the above description that the pawl member has been rocked to release the master wheel 75 and leave it free to be moved by the unit pinion. The gears 73 and 74 form parts of means for determining in which direction the master wheel shall turn and consequently whether addition or subtraction shall take place. This mechanism is not shown in detail as it is or may be the same as that described in my prior application, or other equivalent gear shifting mechanism may be employed. This is actuated by an add and subtract lever 76 having a cam projection 77 (Figure 6) to engage the spring detent 78 to hold the lever in either position.

The trains of gearing by which the rotation of the master wheel is transmitted to the totalizer wheels are substantially the same as in my prior application and each train comprises an index wheel 79 mounted on a shaft 80, a lock gear 81 carried by a lock gear lever 82 pivoted on a rod 83, a dial wheel 84 mounted on shaft 85 and having a gear 86 meshing with a dial intermediate gear 87 which is mounted on a shaft 88 and also meshes with the index wheel 79.

This train of gear being the same as that shown in my prior application and in itself constituting no part of the present invention need not be further described. There are certain differences of construction which form a part of the present invention. The comb plate 89 has one edge pivoted into fingers 90 coiled about the shaft 83 to space the lock gear levers and its other edge pivoted into fingers 91 which are bent around the shaft 85 in the spaces between the totalizer wheels. Obviously these fingers can only be positioned in spaces corresponding to the comma and period in the written number. Another comb plate 92 has one edge pivoted into fingers 93 which are bent around the shaft 80 in order to space the index wheels 79 and its other edge pivoted into fingers 94 which are bent around shaft 88 in order to properly space the dial intermediate wheels. I find these comb plate constructions preferable to the usual spacing washers both on account of simplicity and cheapness of construction and because it is

possible to obtain greater accuracy with much more ease.

Carried by a transverse bar 95 of the traveling register is a comb plate 96 having slots 5 which guide extensions from the lock gear levers 82. Also carried by the bar 95 is a second comb plate 98 having a bent slotted portion 99 which guides the lower ends of the levers 82. These levers 82 are in effect 10 bell crank levers and are spaced on the shaft 83 by the comb fingers 90 and have both arms of the bell crank guided by combs 96 and 99, respectively.

Mounted on the shaft 83 is a series of 15 detent levers 100, each having a detent tooth 101, an offset free end 102, and an angular extension 103. Each extension is normally pressed against the comb plate 98 by a 20 spring finger 104 of a plate 105 fastened to the bar 95. These detent levers do not engage the lock gear levers normally, but when the lock gear levers are moved out of engagement with the index wheels or from the Figure 9 to the Figure 3 position, they 25 move into engagement with the detent levers and are held against displacement. The offset ends 102 of the detent levers are guided by the comb 99 and lie in the slots of this comb above the ends of the levers 82.

It is obvious that the lock gears of each 30 totalizer must be in mesh with their corresponding index wheels while a number is being written, except that the lock gear corresponding to the index wheel which is in mesh with the master wheel at any given time must be disengaged from its index wheel. Also due to the new method of clearing the column register by the return movement of the carriage, it is necessary 35 that the lock gears of the column totalizer be disengaged during such return movement. Moreover, when the lock gears of either totalizer are disengaged, there must be some means of holding the trains of gearing 40 against accidental displacement. The construction by which these results are effected will now be described.

The shaft 106 which carries the master wheel 75 is mounted in the frame plates 2, 3 and 4 and is provided with sleeves 107 and 108. The outer portions of each of these sleeves have ribs 109 and 110, respectively, (see Figure 10). Notched washers 111 and 112 on the plates 2 and 4 engage the ribs 110 and 110 and hold them in proper position. Each rib extends only about half the length of the sleeve and the rib 109 engages the index wheels of the column register as they move towards the left. The rib 110 55 engages the index wheels of the grand totalizer as they move toward the right and reach home position. When the index wheels are engaged by the ribs 109 and 110, the corresponding lock gears are disengaged 60 therefrom or are free to be disengaged.

Carried by the shelf 9 of the register frame are two cam members 113 and 114 of the form shown in Figures 9, 10 and 3. Each cam comprises a straight portion and the ends of one straight portion are bent in 70 a direction opposite to the ends of the other straight portion. The bent end 115 of the cam 114 is flexible for a purpose herein-after mentioned. The straight portions lie in parallel planes which are spaced by a distance slightly less than the width of the arm 97 of the lock lever pawls 82.

When the register lies in home position at the extreme right hand side, the trains of gearing of the grand totalizer will substantially register with the rib 110 and the index wheels of these trains will be engaged thereby. The ends 97 of the lock gears corresponding to the wheels of the column totalizer will lie on the upper side of the cam 85 114 as indicated in Figure 10. As the register begins its movement towards the left, the first index wheel comes into engagement with the master wheel and is operated thereby. Upon the next step to the left the 90 extension 97 of the lock gear lever corresponding to the index wheel which has just been actuated, comes into contact with the under surface of the cam 113 and is moved to cause the lock gear to engage with the 95 index wheel. As the column register continues to move step by step toward the left, each succeeding lock gear is moved into engagement with its index wheel, thus permitting the necessary carrying operations 100 to be properly executed.

After the series of items has been written and recorded in the column totalizer and the register mechanism is moved to the left in position to bring the grand totalizer into operative relation to the master wheel 105. A similar operation takes place as regards the lock levers corresponding to the index wheels of this totalizer. At the same time the index wheels of the column totalizer are moving into engagement with the rib 109 and are held against displacement while the extensions 97 of the lock gear levers 82 pass to the left of the cam 113, thereby locking the index wheel by cam 109 instead of indirectly through cam 113.

On the return movement of the register toward the right the extensions 97 of the lock gear levers successively strike the bent end 115 of the cam 114 and ride upon the upper surface of this cam thereby disengaging from the index wheels permitting the index wheels of the column totalizer to be returned to zero by mechanism hereinafter described. This end 115 is made flexible since the type-writer carriage is usually returned with considerable speed, and it is desirable to have a certain yielding in order to avoid excessive wear due to extreme speed.

It will be noted that at certain times the 130

lock gear levers are disengaged while the index wheels are at the same time out of register with the ribs 110. At this time accidental displacement of the trains of gearings is prevented by mechanism shown in Figure 3, which comprises a rod 116 engaging all of the index wheels. This rod is carried by a frame with two arms, one in the form of a bell crank lever 117, both fulcrumed on a rod 118 and drawn in one direction by a spring 119 attached at one end to the other end of the bell crank lever and at its other end to a stud 102 on the shelf 8. The engagement of the rod 116 with the index wheels is a frictional engagement sufficient to prevent accidental disengagement, which requires the exercise of little power to rotate the train of gearing. As the column register is cleared by the return movement of the carriage, the trains of gearing are turned and the index wheels cam the rod 116 out of their paths.

In a construction such as the present where there is no full stroke mechanism acting upon the down stroke of the type key, there is the possibility of an incomplete operation. The operation of the key may perform one of the two operations which it should perform without performing the other. It may return without computing or printing or it may compute without printing. At this time the operator may be uncertain as to just what has taken place and also as to whether the correct key has been depressed. The invention, therefore, provides an indicating means which will show the last number that has been entered into the computing mechanism during the operation of the column totalizer and the denomination in which said number was written is shown by the position of the totalizer or carriage. This mechanism is best shown in Figures 5, 6 and 8 and will now be described. A rod 121 mounted in the side plates 2 and 3 supports a series of ten indicating members, one of which is shown detached in Figure 8. Each member has an offset ear 123 bent to afford with the body of the member 121 bearing on the rod 121. Each member also has a curved sector portion 124 having a numeral thereon and a depending portion 125 which is struck by an ear 126 on the corresponding bar 24 as it is actuated by the depression of the key. The numeral on each sector corresponds with the digital value of the bar 24 with which that particular sector is associated. Each indicating member is provided with a returning spring 127 attached at one end to the indicating member and at its other end to a rod 128 mounted in the side plates of the frame. These springs tend to draw the indicating members normally against a stop rod 129. Another rod 130 mounted in the side plates supports a sheet metal member 131 which has a portion bent around said

rod and has a series of forwardly extending fingers 132 corresponding to the indicating members. The free end of each finger is provided with a hook 133 which is adapted to hook over an ear 134 on each indicator member 122 when the latter is operated. The member 131 has an upstanding arm 135 having a slot 136 in which is fastened one end of a rod 137, the other end of which is attached to the pawl member 46. 75 75

The operation of this mechanism is as follows. Whenever a key is depressed and the bar 24 actuated, the ear 126 will come in contact with the depending finger 125 of the indicator member 122 corresponding 80 to the denomination of the actuated key. This finger will, therefore, be moved rearwardly and if completely actuated will reach the position of the rear finger in Figure 6. While this operation is taking place, the movement of the bar 24 has through the mediation of the cam gear 33 and associated parts rocked the pawl member 46, pulling rearwardly on the link 137. This rocks the member 131 on the rod 130 and lifts the 85 hook member 133 upward, releasing any indicator member 122, which may have been set previously. It will be remembered that if the key is depressed far enough to completely operate the computing mechanism, the pawl member 46 will be released and returned to normal position before the completion of the down stroke of the key. As soon as the pawl member returns to normal position, the rod 137 will be moved and the 90 fingers 132 moved downward to a position where the hook 133 will engage the ear 134 of the indicator member which has just been moved by the bar 24. When the key is released this auxiliary indicator member which 95 may be read through an opening 138 in the top plate 14, will show the number that has been entered in the computing mechanism and the denomination in which it has been entered. However, if the depression of the 100 key has not been sufficient to set up the number in the computing mechanism and allow the pawl member 46 to return to normal position, then the indicator member will 105 move backward as the key rises and the ear 134 will move forward before the hook 133 drops to a position to detain the same. It 110 may be noted that only one number shows at a time in this auxiliary indicating mechanism but that this is always the last figure 115 which has been set up in the computing mechanism. If therefore, the operator has made an error in depressing a key or has depressed a key insufficiently, the fact is immediately apparent and the error may be 120 corrected at once. 125

The register is caused to travel step by step with the typewriter carriage when the latter is in the computing zones by means of the following mechanism. Attached to 130

the typewriter carriage is a pick-up dog 139 which is substantially the same as that of my prior application except that it cannot be manually moved to released position. This is adapted to engage a detent 140 carried by a member having a portion 141 lying in one plane and a rack portion 142 lying in a different plane (Figures 1 and 6). The portion 141 is guided by a plate 143 attached to the frame by screws and having a semi-circular guide portion 144. To the top plate is adjustably fastened a plate 145 by means of screws 146 and one end 147 thereof is adapted to coact with the cam of the pick-up dog. The other end 148 acts as a stop to limit the movement of the detent 140 in one direction. The operation of these parts is obvious and substantially the same as in my earlier application and need not be further described. The plate 143 has a notch 149 substantially opposite the position of the detent 140 when the register is in home position and this detent 140 is swiveled on the bar 141 so that it can be turned manually to engage the notch 149 and be disengaged from the pick-up dog 139. This construction affords hand releasable means for disengaging the adding mechanism from the carriage of the typewriting machine.

30 The rack 142 meshes with the gear 150 (Figures 5, 6 and 7) carried by a shaft 151 supported at an angle of about 45° in bearing brackets 152 and 153. The other end of the shaft 151 carries a larger gear 154 which 35 meshes with a rack 155 carried by the register frame. Notwithstanding the fact that the pick-up dog 139 engages the detent 140 and causes the carriage and register to move together through the adding zones, it is 40 found desirable to relieve the carriage of the labor of moving the register when traveling step by step in letter space direction. A spiral spring 156 is attached at one end to the right hand side of the register, passed 45 around a pulley 157 carried by a screw stud 158 supported by the frame member 7, and is attached at 159 to the traveling register.

50 In order to secure exact correspondence between the position of the carriage and that of the register, the gear 150 is adjustably mounted on the shaft 151 as in my prior application by means including an eccentric screw 160 (Figure 7) attaching the gear to a block held to the shaft. The eccentric is 55 locked by set screw 161.

Since the register is spring drawn toward the left it is obvious that there must be some means provided for holding the same in the right hand position when the detent 140 and pick-up dog 139 are out of engagement. This is accomplished as follows. Mounted 60 in rearward extensions of the frame plates 2 and 4 is a rock shaft 162. Arms 163 support thereon a metal strip having a straight portion 164 and a spiral cam portion 165.

A depending pin 166 on the typewriter carriage is adapted to engage the cam portion 165 when the carriage is returned and thereby rock the shaft 162. After the pin reaches the straight portion 164 the shaft is merely held against return movement. A collar 167 on the shaft has an arm 168 for a purpose hereinafter set forth and a spring 169 is connected at one end to this arm and at the other end to a pin 170 carried by the register frame member 7. This spring serves to return the shaft 162 to the Figure 1 position when the carriage is again moved to the left and the pin 166 passes off the cam portion 165.

Another collar 171 on the shaft 162 supports a cam member 172 having a cam end 173 (Figures 6 and 7). A bell crank lever 174 fulcrumed about 175 on the frame 7 has a roller 176 carried by one arm in position to be engaged by the cam 173 when the shaft 162 is turned. The first portion of the rotation of the shaft, therefore, rocks the lever 174, while the roller engages the cam 173, but as the roller travels along the straight portion of the member 172, the lever receives no further movement. A bracket 177 is fastened by a screw 178 to the shaft 151 adjacent the gear 150 and carries a projecting pin 179. The parts are so proportioned that at the time the register reaches home position and the detent 140 is released by the pick-up dog 139, the bell crank lever 174 has been rocked to bring a flat portion 180 at the end of one arm thereof against the pin 179 to prevent any reverse rotation of the shaft 151. The position of the parts in Figure 7 is just preceding the end of the movement. It will be noted that a slight further movement of the parts in the direction of the arrows in this figure will bring the pin 179 and the flat portion 180 of the lever in such relation as to prevent reverse rotation of the shaft 151 and the gear 154 and therefore will hold the register in its 110 right hand position.

When the items have been written in the column totalizer and the register is moved to a position to bring the grand totalizer into cooperative relation with the master wheel 115 for the purpose of writing in said grand totalizer the sum appearing in the column totalizer, certain mechanism is thrown into effective condition to prevent the writing of any figures except those set up in the column totalizer and to prevent the writing of these figures in any other than the correct denominational position.

This mechanism will now be described. A projection 181 (Figures 4 and 5) on the traveling register contacts with the roller 182 as the register moves to the left and brings the column totalizer out of the computing zone. This roller 182 is carried by one arm 183 of a bell crank lever pivoted at 130

184 to a bracket on the frame member 2 and having a downward arm 185 drawn in one direction by a spring 186 attached to a stud 187 on the frame. A stop 188 limits the movement of the bell crank lever under the influence of this spring. The arm 185 is connected by a link 189 to a lever 190 pivoted at 191 to a frame. This lever has a hook 192 normally underlying a lever 193 (Figure 3) pivoted at 194. When this hook is moved out of engaging relation to the lever 193, the latter moves counter-clockwise about its pivot due to the weight of the longer arm thereof. A projection 195 on said lever engages an arm 196 on a member 197 (Figures 3 and 6). This member 197 is loosely mounted on a shaft 198 pivoted in the frame plates 2 and 3. A sheet metal plate or member 199 is wrapped about the shaft and extends upward so that its edge 200 normally lies just below the path of the bars 24 as shown in Figure 6. A spring 201 (see Figure 5) is fast at one end to the plate 199 by a screw 202 and at its other end bears against the member 197, the relation being such that the plate and member move together in one direction, but may yield during movement in the other direction.

When the column totalizer has moved to the left as described and the lever 193 has operated the member 197, then the edge of the plate 199 has been moved into a path of the bars 24 so that an actuation of any one of these bars will cause the downturned lug 31 thereon to engage the plate and rock the same together with the member 197. This operates the following devices.

A shaft 203 is mounted to turn in the frame plates 2 and 3 and has fast thereon a plurality of sectors 204 shown in Figures 2, 5 and 6. Each sector lies adjacent a bar 24 and the right hand sector has a rearward extension 205 provided with a pin 206. A lever 207 has a U-shaped portion forming a wide bearing on the shaft 203. A spring 208 has one end hooked to the lever 207, is coiled around the shaft 203 and has its other end engaging the pin 206 on the sector 204. The lever 207 is connected by a link 209 to the member 197 so that when the latter is rocked, the lever 207 will also be rocked and the sectors 204 will move, therefore, when and as long as they are free to move. The spring 208 will permit the lever 207 to move after movement of the sectors is stopped. A spring 210 tends to return the sectors to normal position.

Each sector 204 has a clearance slot 211 and all of these slots are in line when the mechanism is in normal position and each permits passage of an offset lip 212 on the under edge of the associated bar 24. At about the middle of the series one of the sectors has pivoted thereto a link 213, the

other end of which is connected to a digit feeler pivoted on the shaft 70. It may be noted here that in the present construction where only a single master wheel is involved, this digit feeler occupies substantially the 70 position of the second master wheel in my previous construction. Each sector 204 also has an offset portion 215 permitting the passage of the associated lip 212 when the sector has been moved to a certain position. If the sector is moved to any other position, the lip 212 engages the same and stops the movement of the bar 24 before the number represented by the depressed key has been set up in the totalizer. The offsets 215 are arranged in sequence in the different sectors as shown in Figure 2. The movement of the sectors is determined by the digit feeler 214 in the following manner.

Each dial intermediate wheel 87 meshes 85 with a gear tooth 216 (Figures 3, 4 and 9) which has on one face thereof two pins 217. The position of these digit feeler gears 216 varies in accordance with the number appearing in the column totalizer in the corresponding denominations. If the first number to be copied is 5 and the operator strikes the 5 key, the end tooth 218 of the digit feeler will contact one of the pins 217 which of course will be about half the motion from 95 that shown in full lines in Figure 9 where the pins rest against the curved edge 219, which is the complete motion and therefore the zero position. The sectors 204 will be moved so that the sector corresponding to 100 the 5 key will have its offset 215 in line with the bar 24 which will move freely throughout its full stroke, as the lip 212 will pass through the offset. After the lip has passed through this offset, the end 31 of the bar 24 105 will slide off the plate 200 and the plate with the connections to the sectors and the sectors themselves will all return to normal position. On the return movement of the bar 24 the lip 212 will pass through the normal 110 slot 211 in the sector.

But if the number to be copied is 5, the feeler 214 will be stopped by the pin 217 in the 5 position, and if the operator strikes the 6 key or any other key except the 5, the 115 sectors will not be moved to a position to bring the offset 215 on the sector corresponding to this part 24 in line with the lip 212. The lip 212 will, therefore, contact with the sector and prevent complete operation of 120 the key. The parts are so proportioned that this occurs when the key is depressed about one-third of its normal depression. While the totalizer wheel has been operated partially, the release of the key will reverse the 125 operation of said wheel and bring it back to starting position. This operation is possible because of the absence of full stroke mechanism on the down stroke of the keys. It is obvious that it is impossible for the 130

- operator to write any number except that appearing in the column totalizer when the carriage is in position to write the sum and set up the number in the grand totalizer.
- 5 Moreover, this mechanism operates to prevent writing of a figure in the incorrect denominational position. Suppose for example the highest amount to be copied is hundreds and the operator accidentally stops at 10 the thousands position. The first figure to be written will be an integer but the totalizer wheel in thousands position is standing at zero and the key corresponding to the integer cannot be fully depressed.
- 15 Having finished transcribing the total which appears in the column totalizer, which number is the only one that can be written and set up in the grand totalizer at this time, the register is returned to and locked in 20 home position. Just after the register has reached home position, the column totalizer is cleared by the continued movement of the carriage through mechanism about to be described and illustrated particularly in Figures 3, 4 and 5.
- 25 A shaft 219 is mounted between the side frame members 3 and 4 and has loosely mounted thereon a gear 220 fixed to a disc 221. This disc has pivoted to one face 30 thereof a pawl 222 normally pressed in one direction by a spring 223 also carried by said disc. There is also mounted on the shaft 219 a ratchet member 224 having two teeth at diametrically opposite points adapted to 35 cooperate with the pawl 222. This ratchet member is rigid with a cam 225.
- Pivoted on the rod 118 is a series of zero 40 fingers 226 which are tied together by a rod 227 and properly spaced by washers 228 (Figure 4). These zero fingers are in proper position to engage the projections 217 on the gears 216 when the column totalizer is in home or right hand position. It is to be remembered that these pins 217 are 45 engaged by the zero fingers only when the column totalizer is in the right hand position. One of the zero fingers has a downwardly extending part 229 which is engaged by the cam 225 when the latter is rotated.
- 50 When this cam is rotated the zero fingers are all moved from full line to dotted line position of Figure 3. In this movement one or the other of the pins 217 is engaged by either the end or the curved portion 230 of the zero 55 fingers and these gears are cammed to zero position, at the same time returning the totalizer wheels to zero. It will be remembered that the lock gear levers are all released at this time and that the rod 116 is 60 cammed out of holding engagement by the rotation of the trains of gearing. When the zero fingers are fully operated as shown in dotted lines in Figure 3, the curved surface 230 contacts with the two projections 217 65 and prevents overthrow or back lash move-

ment. A spring 231 attached to an ear of the depending part 229 and to the stud 120 tends to return the parts to normal position.

The gear 220 is given its return movement in the following manner. As has been described, when the register moves to the left, the lever 193 is released and one end thereof drops. This end of the lever normally engages the tail of the pawl 222 and holds it out of engagement with the teeth of the ratchet member 224. However, when the lever 193 drops the spring 223 moves the pawl 222 into position to engage the teeth on this ratchet member. After the carriage has moved far enough on its return to bring the register to home position, a continued movement thereof operates the gear 220 in the following manner. To the arm 168 on the shaft 162 which is rotated by the return movement of the carriage is attached a bar 232 having rack teeth 233 on one end to engage the gear 220. An end-wise movement of the bar 232 therefore rotates the gear 220 which has been clutched with the cam 225 as described and the rotation of the latter operates the zero fingers in the manner above set forth. The free end of the bar 232 is supported by a roller 234 mounted on a stud 235. After the movement is nearly completed, a projection 236 on the bar 232 contacts with a bent ear 237 on the end of the lever 193 and rocks the same, lifting the other end against the pawl 222 and moving the same out of engagement with the ratchet, on return movement of the bar 232 under influence of the spring 169. It may be noted that the ratchet has two teeth and that the cam 225 comprises two cam portions so that a complete clearance is obtained by one half a revolution of the gear 220 and associated parts.

It may be that the operator will occasionally move the carriage far enough to the left to bring the grand totalizer into operative position without desiring to clear the column totalizer on the return movement of the carriage. In such case a finger piece 238 attached to the lever 193 is pressed down, which relatches lever 193 in hook 190 which holds the pawl 222 in inoperative position when the carriage is next returned.

It is believed to be unnecessary to recapitulate in detail the operation of the device since each feature has been explained in connection with the description of the structure thereof. It is to be noted that the invention provides a simple and efficient means for performing the character of work which it is desired to carry out and that practically all chance of error has been avoided so far as is possible in devices of this character.

During the writing of the items of the bill and setting them up in the column totalizer, the auxiliary indicating mechanism

shows at any time the last digit which has been registered in the totalizer and the denomination in which it has been entered is indicated by the position of the totalizer. 5 Any error which occurs at this time may be quickly corrected without difficulty.

As soon as the various items have been written and the carriage is moved to a position to write the sum and set up the total 10 in the grand totalizer, mechanism is thrown into position which prevents the inaccurate copying of the total appearing in the column register. There is no necessity at this time for the use of any add or subtract lever or 15 special key of any character. The error check mechanism comes into position automatically upon movement of the carriage and register into the grand totalizer zones.

After the sum is written, the carriage is 20 returned to starting position for the purpose of writing a succeeding bill and the column register is automatically cleared. No manipulation of any key or thought on the part of the operator is necessary to attain 25 this result. In fact it may be noted that the add and subtract key is only used for three purposes; to correct an inaccurate entry in the column totalizer, to enter a credit item in the column totalizer and to 30 clear the grand totalizer when desired.

Figures 11, 12 and 13 show a modified form of error check mechanism in which instead of stopping an incorrect key on the down stroke and preventing the entry of a 35 number in the register the key is permitted to move freely on its down stroke and write the incorrect number, but is prevented from return movement. The operator will, therefore, know that an error has been made and 40 correct the same at once. Many parts of the mechanism are the same as in the previous modification and only those which are different or are necessary for a clear understanding of this form are shown in these 45 figures.

A rock frame 239 is mounted on a shaft 240 which is pivoted in the frame plates 2 and 3 and this frame is normally drawn in one direction by a spring 241. The ends of 50 the sliding bars 24 normally contact with said rocking frame at all times so that the frame is moved each time a key is depressed. The spring 241, therefore, acts as a return spring for all of the sliding bars 24 and the 55 train of mechanism connected thereto.

When the lever 193 is released from its latch exactly as in the previous construction, its end drops not only by its own weight but also because of the tension of a spring 242. 60 Since this lever performs more work in this form of the device than in the other, it is found advisable to add this spring. The downwardly moving end of the lever 193 engages an arm 243 of a bell crank lever 65 pivoted at 244 on a bracket 245 carried by

the frame plate 3. The depending arm 246 of this bell crank lever has a rounded end lying between the sides of a U-shaped bearing 247 of a crank 248 which is slidable on the shaft 240. This crank has a jaw 249 70 (see Figure 12) which engages the rock frame 239 when said crank is moved to the left. Thereafter the frame 239 and the crank 248 will move together whenever the frame is rocked by the depression of a numeral key. It is to be remembered that at this time the grand totalizer is in the computing zone.

A coil spring 250 within which lies a stop plunger 251 connects the upper end of the 80 crank 248 with a crank arm 252. This crank arm is integral or rigid with a sector shaped cam member 253. The locking sectors 254 are all made substantially the same as the locking sectors 204 of the other modification 85 and these sectors together with the crank 252 are positioned on the shaft 255, being spaced by collars and held rigidly by nuts at each side thereof. This shaft (see Figure 12) is mounted between the side plates 2 90 and 3 to allow endwise movement for throwing into and out of engagement purposes. The side movement of this shaft with all its sectors is controlled entirely by the lever 257, which is connected by a wire link 256 95 to bell crank lever 246 and in this way the two parts will always move together, but in opposite direction. That is to say when the jaw 249 on the lever 246 is disconnected from the rock frame 239, the rock shaft 255 with all its locking sectors mounted thereon is also in the disengaged position which in this case is the extreme left hand position as shown in Figure 12.

The digit feeler 214 is substantially unchanged and is connected by link 213 to one of the sectors 254. It is, however, now mounted to slide the extent of one space on its shaft and in order to preserve it normally in correct alignment it is drawn to 100 the right by a spring 258 attached thereto and to the frame plate 3. It is stopped and aligned in this position by a sheet metal bracket 259 carried by the frame member 11. 105

The disconnect key 260 is pivoted at 261 110 and has a link 262 connecting it to the element 66 (Figure 5) so that when the register is in home or extreme right hand position the same result is produced as by the depression of the disconnect lever by hand, 115 and the error check mechanism does not affect the depression of the numeral keys.

Pivoted on a bracket 263 is a bell crank lever, one arm 264 of which projects outwardly through opening in the frame member 3 and underlies the disconnect key lever. The other arm 265 extends downwardly and bears against the cam 253, which is also fast on the shaft 255 and therefore moves 120 the sectors to inactive position.

The lever 193 is provided with an offset extension 266 underlying the arm 243 of the bell crank lever so that the movement of the lever 193 in either direction will operate this bell crank lever and effect connection or disconnection between the frame 239 and the locking sectors. Projecting ears 267 on the slide bars 24 are right angular in shape (Figure 12) having an inclined face 268 and a straight face 269. These ears engage a stop rod 270 to limit the return movement of the parts.

The operation of this modification may be described briefly as follows. When items are being written and entered in the column totalizer, the rocking frame 239 is disconnected from the error check mechanism and the projections 267 on the slide bars 24 move freely to the right of the lock sectors. As soon as the grand totalizer is brought to the computing zone and the lever 193 released as before described, the bell crank pivoted at 244 is operated to effect a lateral as well as a rotative connection between the rocking frame 239 and the lock sectors 254 carried by the shaft 255. The depression of any numeral key will now oscillate the shaft 255 and operate the digit feeler as before. If the digit feeler is stopped early in its movement, the spring 250 will permit the continued movement of the rocking frame 239. If the correct key is operated, this projection 267 will pass through the corresponding slot in the lock sector 254 and return therethrough without interference. However, if an incorrect key is depressed, the projection 267 will not meet a slot in the corresponding lock sector and the inclined face 268 of this projection will engage the side of the lock sector and cam it to the left against the spring 242, thus allowing the continued movement of the slide bar 24 and consequently a complete depression of the key lever. As soon as the projection 267 has passed the lock sector upon the downward movement of the key, the spring 242 will immediately return the lock sector to its right hand position and on the return movement of the slide bar 24 the straight face 269 of the projection 267 will engage the lock sector and prevent return movement of the bar 24 and consequently prevent return movement of the depressed key. The attention of the operator is thus called to the fact that an error has been made. To release the depressed key it is merely necessary to press the disconnect lever which acting upon the arm 264 of the bell crank lever causes the other arm 265 to engage the cam 253, thereby moving the shaft 255 and all of the lock sectors to the left sufficiently to release the projection 267 from the lock sector which has held it against return movement. The depressed key is therefore

permitted to return to normal position and the error may be corrected at once.

When the lever 193 is rocked in the opposite direction, which rocking movement is produced exactly as in the first modification and as fully described above, the upward movement of the extension 266 engaging under the arm 243 of the bell crank lever will move the arm 246 of this lever in such manner as to disengage the jaw 249 from the frame 239 and thus break the connection between this frame and the locking sectors and also shift them to the left.

It is desirable to provide additional means for accurately alining the register wheels especially during an extended automatic carrying operation. One feature of the present invention is the provision of an additional alining gear and cooperating pawl for this purpose. This also allows considerable extra clearance in the manufacture of the register gears since this alining mechanism will pick up all lost motion and in effect reduces the number of wheels that are carried in a single train of mechanism.

Devices intended for this purpose are shown in Figures 14 and 15. The construction involves relatively few changes in the form previously described and none whatever in the train of gearing including the master wheel or the master wheel pawl. The return spring 271 for the master wheel pawl is somewhat differently located. The same plate 44 which supports the master wheel pawl pivot shaft 45 and the shaft itself are extended and an auxiliary alining pawl 272 is mounted on said shaft. The bent portion 273 of the plate 44 preserves the pawls in proper relation to each other.

An auxiliary alining gear 274 is mounted on a shaft 275 which supports the master wheel and spacing collars 276 preserve the proper relation of these parts. This auxiliary wheel 274 is exactly the same as the master wheel and engages a wheel in the register located several spaces to the left of the wheel engaged by the master wheel. Normally the pawl 272 is drawn away from the gears 274 by means of a spring 276 but is limited in its movement under the influence of this spring by the engagement of an offset ear 277 on the pawl with a pin 278 carried by a frame member.

The crank arm 279 on the rock shaft 54 corresponds generally to the arm 56 in the construction previously described and has a pin or roller 57 cooperating with the tail of the pawl 46 in the same manner. The crank arm 279 is, however, extended further than is the arm 56 and carries a second pin or roller 280 extending to a position to coact with the tail 281 of the auxiliary pawl 272. It is noted that the crank arm 279 with the engaging members 57 and 280 is located be-

tween the tails of the two pawls for reasons which will be understood from a description of the operation.

Figures 14 and 15 show the parts in normal relation with the pawl 46 engaging the master wheel 75 and the auxiliary pawl 272 out of engagement with the auxiliary wheel 274. Upon the down stroke of the key the cam 38 engages the rocking member 55, thereby rocking the pin 57 against the tail of the master wheel pawl 46 and moving the pawl out of engagement with the master wheel. At this time there is no operation on the auxiliary pawl 272. As soon as the cam 38 disengages the member 55, the latter snaps back to position under the influence of its returning spring and the pin 280 will strike against the tail 281 of the pawl 272 with sufficient force to throw it into engagement with the auxiliary alining wheel 274 and thus properly aline the gears. This takes place just before the complete depression of the key. As soon as the key starts to rise, the cam 38 again engages the member 55 and rocks it in the opposite direction or counterclockwise direction in Figure 14 whereupon the pin 280 engages the tail 281 of the pawl 272 and positively moves the same into engagement with the auxiliary alining wheel 274 even if it had moved out of engagement therewith. The action of these parts can be very readily regulated by varying the weight of the crank arm 279 and the tension of the spring 276.

It is obvious that this construction provides very simple and efficient means for assisting in the alinement of the trains of gearing which in no way interferes with the normal action of the parts or with their usual construction.

The various results above described are obtained in each case by simple and compact mechanism which requires substantially no attention on the part of the operator except the manipulation of the proper numeral keys and the return of the carriage. It is obvious that parts of the mechanism may be employed with devices of otherwise widely different character and that various detail changes may be made without in any way departing from the spirit of the invention, which is to be regarded as limited only by the scope of the appended claims.

I claim as my invention:

1. A computing mechanism comprising a travelling totalizer, means for setting up a number therein, and means for clearing said totalizer only after its return movement.

2. A computing mechanism comprising a travelling totalizer, means for setting up a number therein, means for advancing said totalizer beyond its zone of computation, and means for clearing said totalizer only after its return movement from said advanced position.

3. A computing mechanism comprising a column totalizer, a grand totalizer, means for setting up a number in either totalizer, and automatic means for clearing the column totalizer after a number has been set up in the grand totalizer.

4. A computing mechanism comprising a column totalizer, a grand totalizer, means for setting up a number in either totalizer, and means for clearing the column totalizer only after its return movement from a position where the grand totalizer has been positioned in its effective zone.

5. A computing mechanism comprising a column totalizer, a grand totalizer, means for setting up a number in either totalizer, means for clearing the column totalizer only after its return movement from a position where the grand totalizer has been positioned in its effective zone, and manual means for disabling said clearing means.

6. A computing mechanism comprising a plurality of travelling totalizers, means for setting up a number in either totalizer, and means for automatically clearing one totalizer only after the other totalizer has been in its effective zone.

7. A computing mechanism comprising a plurality of travelling totalizers, means for setting up a number in either totalizer, means for automatically clearing one totalizer only after the other totalizer has been in its effective zone, and means for disabling said clearing means.

8. A computing mechanism comprising a column totalizer, means for setting up a number therein when the totalizer is in computing zone, means for advancing the totalizer to another zone, and means for returning said totalizer to home position and automatically clearing the same.

9. A computing mechanism comprising a column totalizer, means for setting up a number therein when the totalizer is in computing zone, means for advancing the totalizer to another zone, means for returning said totalizer to home position and automatically clearing the same, and means for disabling said clearing means.

10. A computing mechanism comprising a column totalizer, a grand totalizer, means for setting up a number in either totalizer, means for advancing the column totalizer past its computing zone to set up a number in the grand totalizer, means for returning the totalizers to home position and means for thereafter automatically clearing the column totalizer.

11. A combined typewriting and computing mechanism comprising a travelling carriage having a to and fro movement, a travelling totalizer, means for setting up a number in the totalizer, and means for clearing the totalizer by the return movement of the carriage.

12. A combined typewriting and computing mechanism comprising a travelling carriage having a to and fro movement, a travelling totalizer, means for setting up a number in the totalizer, means for advancing said totalizer beyond its zone of computation, and means for clearing the totalizer by the return movement of the carriage from said advanced position. 65
13. A combined typewriting and computing mechanism comprising a travelling carriage having a to and fro movement, a travelling totalizer, means for setting up a number in the totalizer, means for clearing the totalizer by the return movement of the carriage, and means for disabling said clearing mechanism to permit return of the carriage without clearing the totalizer. 70
14. A combined typewriting and computing mechanism comprising a traveling carriage having a to and fro movement, a travelling totalizer, means for setting up a number in the totalizer, means for advancing said totalizer beyond its zone of computation, means for clearing the totalizer by the return movement of the carriage from said advanced position, and means for disabling said clearing mechanism to permit return of the carriage without clearing the totalizer. 75
15. A combined typewriting and computing mechanism comprising a travelling carriage having a to and fro movement, a travelling totalizer, means for setting up a number in the totalizer, means for returning the totalizer to home position by the first part of the return movement of the carriage and means for clearing the totalizer by the subsequent part of the return movement of the carriage. 80
16. A combined typewriting and computing mechanism comprising a travelling carriage having a to and fro movement, a travelling totalizer, means for setting up a number in the totalizer, means for returning the totalizer to home position by the first part of the return movement of the carriage, means for clearing the totalizer by the subsequent part of the return movement of the carriage, and means for disabling said clearing means to permit return of the carriage without clearing the totalizer. 85
17. A combined typewriting and computing mechanism comprising a travelling carriage having a to and fro movement, a plurality of travelling totalizers, means for setting up a number in either totalizer, and means for clearing one totalizer by the return movement of the carriage. 90
18. A combined typewriting and computing mechanism comprising a travelling carriage having a to and fro movement, a plurality of travelling totalizers, means for setting up a number in either totalizer, means for clearing one totalizer by the return movement of the carriage, and means for disabling said clearing mechanism. 95
19. A combined typewriting and computing mechanism comprising a travelling carriage having a to and fro movement, a column totalizer, a grand totalizer, means for setting up a number in either totalizer when it is in its effective computing zone, and means for clearing the column totalizer by the return movement of the carriage only after the grand totalizer has been in its effective zone. 100
20. A combined typewriting and computing mechanism comprising a travelling carriage having a to and fro movement, a column totalizer, a grand totalizer, means for setting up a number in either totalizer when it is in its effective zone, means for returning the totalizers to home position, and means for thereafter clearing the column totalizer by the continued movement of the carriage. 105
21. A combined typewriting and computing mechanism comprising a travelling carriage, a travelling totalizer, normally inoperative clearance means therefor, and means controlled by the forward movement of the totalizer beyond a predetermined point to render said clearance means operative. 110
22. A combined typewriting and computing mechanism comprising a travelling carriage having a to and fro movement, a travelling totalizer, normally ineffective clearance means therefor, means controlled by the forward movement of the totalizer beyond a predetermined point to render the clearance means effective, and means for operating said clearance means upon the return movement of the carriage. 115
23. A combined typewriting and computing mechanism comprising a travelling carriage having a to and fro movement, a travelling totalizer, normally ineffective clearance means therefor, means controlled by the forward movement of the totalizer beyond a predetermined point to render the clearance means effective, means for operating said clearance means upon the return movement of the carriage, and means for returning the clearance means to ineffective position after the completion of the clearance operation. 120
24. A combined typewriting and computing mechanism comprising a travelling carriage, a travelling totalizer, normally ineffective clearance means therefor, and automatic means for successively rendering said clearance means effective, operating it, and returning it to ineffective position. 125
25. A combined typewriting and computing mechanism comprising a travelling carriage having a to and fro movement, a travelling column totalizer, a travelling grand totalizer, normally ineffective clearance means for the column totalizer, means controlled by the movement of the grand to-

- talizer into its computing zone for rendering said clearance means effective, and means for operating said clearance means upon the return movement of the carriage.
26. A combined typewriting and computing mechanism comprising a travelling carriage having a to and fro movement, a travelling column totalizer, a travelling grand totalizer, normally ineffective clearance means for the column totalizer, means controlled by the movement of the grand totalizer into its computing zone for rendering said clearance means effective, means for operating said clearance means upon the return movement of the carriage, and manual means for disabling the clearance means to permit the return of the carriage without operating the same.
27. A combined typewriting and computing mechanism comprising a travelling carriage having a to and fro movement, a travelling column totalizer, a travelling grand totalizer, normally ineffective clearance means for the column totalizer, means controlled by the movement of the grand totalizer into its computing zone for rendering said clearance means effective, means for operating said clearance means upon the return movement of the carriage, and means for returning the clearance means to ineffective position by a subsequent portion of the return movement of the carriage.
28. A combined typewriting and computing mechanism comprising a travelling carriage having a to and fro movement, a travelling register comprising a plurality of totalizers, a clearance means for one of said totalizers which is ineffective while the register is in one computing zone but is automatically rendered effective by movement of the register to a second computing zone, and means operated by the return movement of the carriage to operate said clearance means.
29. A combined typewriting and computing mechanism comprising a travelling carriage having a to and fro movement, a travelling register comprising a plurality of totalizers, a clearance means for one of said totalizers which is ineffective while the register is in one computing zone but is automatically rendered effective by movement of the register to a second computing zone, and means operated by the return movement of the carriage to operate said clearance means and thereafter return it to ineffective position.
30. A combined typewriting and computing mechanism comprising a travelling carriage, a travelling register comprising a plurality of totalizers, a clearance means for one of said totalizers, a latch for holding said means normally in ineffective position, and means operated by the travel of the register for releasing said latch and permitting said clearance means to move to effective position.
31. A combined typewriting and computing mechanism comprising a travelling carriage having a to and fro movement, a travelling register comprising a plurality of totalizers, a clearance means for one of said totalizers, a latch for holding said means normally in ineffective position, means operated by the travel of the register for releasing said latch and permitting said clearance means to move to effective position, and means for operating said clearance means by the return movement of the carriage.
32. A combined typewriting and computing mechanism comprising a travelling carriage, a travelling register comprising a plurality of totalizers, a clearance means for one of said totalizers, a latch for holding said means normally in ineffective position, means operated by the travel of the register for releasing said latch and permitting said clearance means to move to effective position, and automatic means for placing said clearance means in ineffective position under control of said latch after the clearance operation has been effected.
33. A combined typewriting and computing mechanism comprising a travelling carriage, a travelling register comprising a plurality of totalizers, a clearance means for one of said totalizers, a latch for holding said means normally in ineffective position, means operated by the travel of the register for releasing said latch and permitting said clearance means to move to effective position, and manual means for placing said clearance means in ineffective position as desired.
34. A combined typewriting and computing mechanism comprising a travelling carriage having a to and fro movement, a travelling register comprising a plurality of totalizers, a clearance means for one of said totalizers, a latch for holding said means normally in ineffective position, means operated by the travel of the register for releasing said latch and permitting said clearance means to move to effective position, means for operating said clearance means by the return movement of the carriage, and means for placing said clearance means in effective position under control of the latch after it has been thus operated.
35. A combined typewriting and computing mechanism comprising a travelling carriage having a to and fro movement, a travelling register comprising a plurality of totalizers, a clearance means for one of said totalizers, a latch for holding said means normally in ineffective position, means operated by the travel of the register for releasing said latch and permitting said clearance

means to move to effective position, means for operating said clearance means by the return movement of the carriage, and manual means for placing said clearance means in ineffective position under control of the latch to permit return movement without clearing.

36. A combined typewriting and computing mechanism comprising a travelling carriage having a to and fro movement, a travelling totalizer, clearance means for said totalizer, a member operated by the return movement of the carriage, a train of connections between said member and said clearance means, said train of connections being normally broken, and means for completing said train by the advance movement of the totalizer to a given position.

37. A combined typewriting and computing mechanism comprising a travelling carriage having a to and fro movement, a travelling totalizer, clearance means for said totalizer, a reciprocating rack operating by the return movement of the carriage, a normally ineffective train of connections between the rack and the clearance means, and means operated by the advance movement of the totalizer to a given position for rendering said train effective.

38. A combined typewriting and computing mechanism comprising a travelling carriage having a to and fro movement, a travelling totalizer, clearance means for said totalizer, a reciprocating rack operating by the return movement of the carriage, a normally ineffective train of connections between the rack and the clearance means, means operated by the advance movement of the totalizer to a given position for rendering said train effective, and manual means for placing said train of connections in ineffective condition at any time.

39. A combined typewriting and computing mechanism comprising a travelling carriage having a to and fro movement, a travelling totalizer, clearance means for said totalizer, a reciprocating rack operating by the return movement of the carriage, a normally ineffective train of connections between the rack and the clearance means, means operated by the advance movement of the totalizer to a given position for rendering said train effective, and means whereby the train is automatically returned to ineffective condition after the clearance operation.

40. A combined typewriting and computing mechanism comprising a traveling carriage having a to and fro movement, a travelling totalizer, clearance means for said totalizer, a member operated by the return movement of the carriage, a train of connections between said member and said clearance means including pawl and ratchet mechanism normally disengaged, and means

controlled by the movement of the totalizer to a predetermined position for engaging said pawl and ratchet to enable said clearance mechanism to be operated by the movement of said member.

41. A combined typewriting and computing mechanism comprising a travelling carriage having a to and fro movement, a travelling totalizer, clearance means for said totalizer, a member operated by the return movement of the carriage, a train of connections between said member and said clearance means including pawl and ratchet mechanism normally disengaged, means controlled by the movement of the totalizer to a predetermined position for engaging said pawl and ratchet to enable said clearance mechanism to be operated by the movement of said member, and manual means for disengaging said pawl and ratchet when desired.

42. A combined typewriting and computing mechanism comprising a travelling carriage having a to and fro movement, a travelling totalizer, clearance means for said totalizer, cam mechanism for operating said clearance means, a normally disengaged pawl and ratchet mechanism for operating said cam, means controlled by the movement of the totalizer to a predetermined position for engaging said pawl and ratchet, and means for operating said pawl and ratchet by the return movement of the carriage.

43. A computing mechanism comprising a travelling member, trains of mechanism adapted for setting up and adding numbers, an auxiliary gear in each of said trains, pins on said gears, and means operated by the movement of said travelling member for engaging said pins to rotate said auxiliary gears and return each train of mechanism to zero position.

44. A computing mechanism comprising a driving member, trains of mechanism adapted for setting up and adding numbers, an auxiliary gear in each of said trains, pins on said gears, cam means for engaging said pins to rotate said auxiliary gears and return each train of mechanism to zero position and a rotary cam member to operate said cam means.

45. A computing mechanism comprising a travelling totalizer having trains of mechanism adapted for setting up and adding numbers, an auxiliary gear in each of said trains, pins on said gears, means adapted to engage said pins and rotate said auxiliary gears to clear the totalizer, normally ineffective means to operate said engaging means, and mechanism controlled by the advance of the totalizer to a predetermined point for rendering said operating means effective.

46. A computing mechanism comprising

- a travelling totalizer having trains of mechanism adapted for setting up and adding numbers, automatic means for clearing said totalizer placed in effective position only 5 when the totalizer has advanced to a pre-determined point, and means whereby said automatic means is operated only after the totalizer returns to home position.
47. A combined typewriting and computing mechanism comprising a travelling totalizer, a travelling carriage having a to and fro movement, each train of mechanism in the totalizer including an auxiliary gear, pins on said gears, a cam member for co-operation with the pins on each gear, and means operated by the return movement of the carriage to move said cam members to rotate said gears and thereby clear the totalizer.
48. A combined typewriting and computing mechanism comprising a travelling totalizer, a travelling carriage having a to and fro movement, each train of mechanism in the totalizer including a lock gear and an auxiliary gear, pins on the auxiliary gears, means adapted to engage said pins and rotate the auxiliary gears to clear the totalizer, means holding the lock gears disengaged at this time, and means operated by the return movement of the carriage to operate said clearing means.
49. A combined typewriting and computing mechanism comprising a travelling totalizer, a travelling carriage having a to and fro movement, each train of mechanism in the totalizer including a lock gear and an auxiliary gear, pins on the auxiliary gears, means adapted to engage said pins and rotate the auxiliary gears to clear the totalizer, means holding the lock gears disengaged at this time, yielding detent means for holding the trains against accidental displacement when the lock gears are disengaged, and means operated by the return movement of the carriage to operate said clearing means.
50. A combined typewriting and computing mechanism comprising a travelling carriage having a to and fro movement, a travelling totalizer, clearance means for said totalizer, a rock shaft, a cam thereon, and means on the carriage which on its return movement engages the cam and rocks the shaft to operate said clearance means.
51. A combined typewriting and computing mechanism comprising a travelling carriage having a to and fro movement, a travelling totalizer, clearance means for said totalizer, a rock shaft, cam means thereon, means forming an operative connection between the rock shaft and the clearance means during the movement of the rock shaft in one direction only, and means on the carriage which on its return movement engages the cam and thereby operates said clearance means.
52. A combined typewriting and computing mechanism comprising a travelling carriage having a to and fro movement, a travelling totalizer, clearance means for said totalizer, a rock shaft, normally ineffective one-way connections between the rock shaft and the clearance mechanism, means for rendering said connections effective, and means for operating the rock shaft on the return movement of the carriage.
53. A combined typewriting and computing mechanism comprising a travelling carriage having a to and fro movement, a travelling totalizer, clearance means for said totalizer, a rock shaft, normally ineffective one-way connections between the rock shaft and the clearance mechanism, means for rendering said connections effective; means for operating the rock shaft on the return movement of the carriage, and means for returning said connections to ineffective condition after the operation of the clearance mechanism.
54. A combined typewriting and computing mechanism comprising a travelling carriage having a to and fro movement, a travelling totalizer, clearance means for said totalizer, and means whereby the return movement of the carriage operates said clearance means.
55. A combined typewriting and computing mechanism comprising a travelling carriage having a to and fro movement, a travelling totalizer, clearance means for said totalizer, a carriage operated member, normally ineffective connections between said member and the clearance means, means for rendering said connections effective, and means whereby the return movement of the carriage thereafter will return the totalizer to home position and clear the totalizer thereafter.
56. A combined typewriting and computing mechanism comprising a travelling carriage having a to and fro movement, a travelling totalizer, clearance means for said totalizer, a carriage operated member, normally ineffective connections between said member and the clearance means, means for rendering said connections effective; and means whereby the return movement of the carriage thereafter will return the totalizer to home position, clear the totalizer, and then return the connections to ineffective condition.
57. A computing mechanism comprising a totalizer, a plurality of keys operated in sequence for setting up numbers in said totalizer, and auxiliary indicating mechanism which identifies only the last key which has been depressed sufficiently to enter into the totalizer the number corresponding thereto.

58. A computing mechanism comprising a totalizer, a plurality of keys for setting up numbers in said totalizer, a rocking indicator member for each key bearing a number corresponding thereto, means for rocking the associated indicator member upon the operation of any key, and means controlled from the computing mechanism for detaining said member with the number visible to the operator only if the key has been depressed sufficiently to enter the number in the totalizer.
59. A computing mechanism comprising a totalizer, a plurality of keys for setting up numbers in said totalizer, a rocking indicator member for each key bearing a number corresponding thereto, means for moving the rocking member to a position rendering the indication thereon visible upon depression of the key corresponding thereto, and means controlled from the computing mechanism for detaining it in this position only if the key has been depressed sufficiently to set up the number in the totalizer.
60. A computing mechanism comprising a totalizer including a master wheel and pawl therefor, a plurality of keys for setting up numbers in the totalizer, indicating means for showing which key has been last depressed sufficiently to enter the number into the totalizer, and means controlled by the master wheel pawl for retaining the indicating means in operated position.
61. A computing mechanism comprising a totalizer including a master wheel and pawl therefor, a plurality of keys for setting up numbers in the totalizer, indicating means for showing which key has been last depressed sufficiently to enter the number into the totalizer, means operated by the keys for moving said indicating means and means controlled by the master wheel pawl for retaining the indicating means in operated position and releasing the indicator previously set.
62. A computing mechanism comprising a totalizer, a plurality of keys for setting up numbers in said totalizer, a rocking indicator member for each key bearing a number corresponding thereto, means for detaining in visible position the indicator member corresponding to any key when the key has been completely depressed, and means controlled from the computing mechanism for releasing the indicator previously set.
63. A computing mechanism comprising a visible totalizer, a plurality of keys for setting up numbers in sequence in the totalizer, means entirely independent of the totalizer for indicating which key has last been fully depressed, and means whereby the setting of the indicating means corresponding to one key releases a previously set indicating means.
64. A computing mechanism comprising in letter space direction, means whereby the
- a visible totalizer, a plurality of keys operable individually for setting up numbers in sequence in the totalizer, a plurality of independent indicators, one corresponding to each key, means for retaining an indicator in effective position when the key has been fully operated, and means for releasing a previously set indicator at the same time.
65. A computing mechanism comprising a visible totalizer, a plurality of keys operable individually for setting up numbers in sequence in the totalizer, a plurality of indicators spring pressed to ineffective position, means for moving the associated indicator whenever a key is depressed, and means for holding said indicator in effective position only when the key has been depressed sufficiently to enter the corresponding number in the totalizer.
66. A computing mechanism comprising a totalizer including a master wheel and pawl therefor, a plurality of keys for setting up numbers in the totalizer, a plurality of separate indicating means spring pressed to normal position, a member for retaining any one of said indicators in indicating position when its corresponding key has been fully operated, and means whereby said member is controlled from the master wheel pawl.
67. A combined typewriting and computing mechanism comprising a travelling carriage, a totalizer travelling in unison therewith in both directions through a predetermined zone, and means independent of the typewriter carriage tending to move the totalizer in letter space direction.
68. A combined typewriting and computing mechanism comprising a travelling carriage, a travelling totalizer, means causing the carriage and totalizer to move in unison at all times through a predetermined zone, and independent spring means tending to move the totalizer in letter space direction.
69. A combined typewriting and computing mechanism comprising a travelling carriage, a travelling totalizer, means independent of the carriage for moving the totalizer in letter space direction or from right to left, and means whereby the carriage and totalizer move together in the return movement.
70. A combined typewriting and computing mechanism comprising a travelling carriage, a travelling totalizer, means independent of the carriage urging the totalizer in letter space direction, and means whereby the return movement of the carriage returns the totalizer to home position.
71. A combined typewriting and computing mechanism comprising a travelling carriage, a travelling totalizer, means independent of the carriage urging the totalizer in letter space direction, means whereby the

return movement of the carriage returns the totalizer to home position, and means for locking the totalizer in home position.

72. A combined typewriting and computing mechanism comprising a travelling carriage, a travelling totalizer, means independent of the carriage for urging the totalizer in letter space direction, and means whereby the return movement of the carriage automatically returns the totalizer to home position, locks it in said position, and breaks the connection between the carriage and totalizer.

73. A combined typewriting and computing mechanism comprising a travelling carriage, a travelling totalizer, means including a sliding rack connected to the carriage during a predetermined zone on its return movement, connections between said rack and the totalizer, and means whereby said connections are locked against movement when said rack and carriage are disconnected.

74. A combined typewriting and computing mechanism comprising a travelling carriage, a travelling totalizer, means including a sliding rack connected to the carriage during a predetermined zone on its return movement, connections between said rack and the totalizer, means whereby said connections are locked against movement when said rack and carriage are disconnected, and means operated by the carriage movement for controlling said locking means.

75. A combined typewriting and computing mechanism comprising a travelling carriage, a travelling totalizer, a train of connections whereby the carriage in its return movement returns the totalizer to home position and is then disconnected therefrom, cam means operated by the return movement of the carriage, and means operated by said cam means to a position to lock the totalizer in home position when it is disconnected from the carriage.

76. A combined typewriting and computing mechanism comprising a travelling carriage, a travelling totalizer, a train of connections including a shaft whereby the carriage in its return movement returns the totalizer to home position and is then disconnected therefrom, cam means operated by the return movement of the carriage, and means moved by the cam means to a position to prevent reverse rotation of the shaft when the totalizer is in home position and disconnected from the carriage.

77. A combined typewriting and computing mechanism comprising a travelling totalizer, means for entering numbers in said totalizer when it is in a certain zone, and error check means rendered effective by a previous movement of the totalizer to a different zone to check the writing of an incorrect total.

78. A combined typewriting and computing mechanism comprising a travelling totalizer, key operated means for entering numbers in said totalizer when it is in a certain zone, and error check means rendered effective by the movement of the totalizer to a different zone which prevents a complete operation of an incorrect key in writing the total.

79. A combined typewriting and computing mechanism comprising a travelling totalizer, means for entering numbers in said totalizer when it is in a certain zone, and error check means which becomes automatically effective when the totalizer is moved to another zone and interferes with the action of the typewriting mechanism unless the correct total is written digit by digit.

80. A combined typewriting and computing mechanism comprising a travelling totalizer, means for entering numbers in said totalizer when it is in a certain zone, and error check means rendered effective solely by a previous movement of the totalizer to another zone which interferes with the operation of the numeral typewriter keys unless the total is correctly written in that zone.

81. A combined typewriting and computing mechanism comprising a travelling totalizer, means for entering numbers in said totalizer when it is in a certain zone, error check means rendered effective by a previous movement of the totalizer to a different zone to check the writing of an incorrect total, and means for automatically returning said error check means to ineffective position.

82. A combined typewriting and computing mechanism comprising a travelling totalizer, key operated means for entering numbers in said totalizer when it is in a certain zone, error check means rendered effective by the movement of the totalizer to a different zone which prevents a complete operation of an incorrect key in writing the total, and means for automatically returning said error check means to ineffective position.

83. A combined typewriting and computing mechanism comprising a travelling totalizer, means for entering numbers in said totalizer when it is in a certain zone, error check means which becomes automatically effective when the totalizer is moved to another zone and interferes with the action of the typewriting mechanism unless the correct total is written digit by digit, and means for automatically returning said error check means to ineffective position.

84. A combined typewriting and computing mechanism comprising a travelling totalizer, means for entering numbers in said totalizer when it is in a certain zone, error check means rendered effective solely by a previous movement of the totalizer to

another zone which interferes with the operation of the numeral typewriter keys unless the total is correctly written in that zone, and means for automatically returning said

6 error check means to ineffective position.

85. A combined typewriting and computing mechanism comprising a travelling register having column and grand totalizers, means for entering numbers in either totalizer when it is in the computing zone, and error check mechanism controlled by the column totalizer which prevents the complete operation of incorrect keys when the total is being entered into the grand totalizer.

86. A combined typewriting and computing mechanism comprising a travelling register having column and grand totalizers, means for entering numbers in either totalizer when it is in the computing zone, and error check mechanism which prevents the complete operation of incorrect keys when the total is being entered into the grand totalizer, said mechanism being automatically rendered effective by the movement of the register to bring the grand totalizer into the computing zone.

87. A combined typewriting and computing mechanism comprising a travelling register having column and grand totalizers, a travelling carriage, means for entering numbers in either totalizer when it is in the computing zone, error check mechanism automatically rendered effective by the movement of the register to bring the grand totalizer into the computing zone and preventing complete operation of incorrect keys at this time, and means operated by the return movement of the carriage for restoring said mechanism to ineffective condition.

88. A combined typewriting and computing mechanism comprising a travelling register having column and grand totalizers, a travelling carriage, means for entering numbers in either totalizer when it is in the computing zone, keys for operating said means, error check mechanism normally in ineffective relation to said means, and devices operated by the movement of the register to a position to bring the grand totalizer into the computing zone which render said mechanism effective to prevent complete operation of incorrect keys at this time.

89. A combined typewriting and computing mechanism comprising a travelling register having column and grand totalizers, a travelling carriage, means for entering numbers in either totalizer when it is in the computing zone, keys for operating said means, error check mechanism normally in ineffective relation to said means, devices operated by the movement of the register to a position to bring the grand totalizer into the computing zone which render said mechanism effective to prevent complete operation

of incorrect keys at this time, and means operated by the return movement of the carriage to return said mechanism to ineffective condition.

90. A combined typewriting and computing mechanism comprising a travelling register including column and grand totalizers, a travelling carriage, numeral keys, devices operated thereby for setting up a number in either totalizer when it is in the computing zone, and error check mechanism comprising a member normally out of the path of said devices and means controlled by the movement of the register to bring said member into the path of said devices and render the error check mechanism effective when the grand totalizer is in the computing zone.

91. A combined typewriting and computing mechanism comprising a travelling register including column and grand totalizers, a travelling carriage, numeral keys, devices operated thereby for setting up a number in either totalizer when it is in the computing zone, error check mechanism comprising a member normally out of the path of said devices and means controlled by the movement of the register to bring said member into the path of said devices and render the error check mechanism effective when the grand totalizer is in the computing zone, and means whereby the return movement of the carriage returns the member to its normal position.

92. A combined typewriting and computing mechanism comprising a travelling register having column and grand totalizers, a travelling carriage, a series of keys for setting up a number in either register when it is in the computing zone, and error check mechanism which becomes operative automatically when the grand totalizer is in the computing zone and prevents the complete operations of the keys to set up therein any number except the total appearing in the column totalizer.

93. A combined typewriting and computing mechanism comprising a travelling carriage, a travelling register including column and grand totalizers, a series of numeral keys, a sliding member operated by each key and operating mechanism to set up a number in either totalizer when it is in the computing zone, and means controlled by the movement of the register for interfering with the complete operation of an incorrect key whenever the grand totalizer is in the computing zone.

94. A combined typewriting and computing mechanism comprising a travelling totalizer, key operated means for entering numbers in said totalizer when it is in a certain zone, and error check means rendered effective by the movement of the totalizer to a different zone which prevents the complete depression of an incorrect key.

95. A combined typewriting and computing mechanism comprising a travelling totalizer, key operated means for entering numbers in said totalizer when it is in a certain zone, and error check means rendered effective by the movement of the totalizer to a different zone which prevents the complete depression of any keys except those corresponding to the total appearing in the column totalizer.
96. A combined typewriting and computing mechanism comprising a travelling totalizer, key operated means for entering numbers in said totalizer when it is in a certain zone, error check means rendered effective by the movement of the totalizer to a different zone which prevents the complete depression of an incorrect key, and means for automatically returning said error check mechanism to ineffective position.
97. A combined typewriting and computing mechanism comprising a travelling totalizer, key operated means for entering numbers in said totalizer when it is in a certain zone, error check means rendered effective by the movement of the totalizer to a different zone which prevents the complete depression of any keys except those corresponding to the total appearing in the column totalizer, and means for automatically returning said error check mechanism to ineffective position.
98. A combined typewriting and computing mechanism comprising a travelling register having column and grand totalizers, key operated means for entering numbers in either totalizer when it is in the computing zone, and error check mechanism which prevents a complete depression of inaccurate keys when the total is being entered into the grand totalizer.
99. A combined typewriting and computing mechanism comprising a travelling register having column and grand totalizers, key operated means for entering numbers in either totalizer when it is in the computing zone, and error check mechanism which prevents a complete depression of inaccurate keys when the total is being entered into the grand totalizer, said mechanism being rendered effective automatically by the movement of the register to bring the grand totalizer into the computing zone.
100. A combined typewriting and computing mechanism comprising a travelling carriage, a travelling register having column and grand totalizers, key operated means for entering numbers in either totalizer when it is in the computing zone, error check mechanism automatically rendered effective by the movement of the register to bring the grand totalizer into the computing zone and preventing the complete depression of incorrect keys at this time, and means operated by the return movement of the carriage

for restoring said mechanism to ineffective condition.

101. A combined typewriting and computing mechanism comprising a travelling carriage, a travelling register having column and grand totalizers, a series of numeral keys, a sliding member corresponding to each key and operating mechanism to set up a number in either totalizer when it is in the computing zone, and error check mechanism automatically operative when the grand totalizer is in the computing zone to prevent a complete movement of said sliding member and thus prevents the entry of a number into the grand totalizer if an incorrect key has been depressed.

102. A combined typewriting and computing mechanism comprising a travelling carriage, a travelling register having both column and grand totalizers, a series of auxiliary gears in said column totalizer, and means cooperating with said gears to prevent complete depression of an incorrect key when the grand totalizer is in the computing zone.

103. A combined typewriting and computing mechanism comprising a travelling carriage, a travelling register having both column and grand totalizers, a series of auxiliary gears in said column totalizer, projections on said gears, and means stopped in their movement by contact with said projections to prevent complete depression of an incorrect key when the grand totalizer is in the computing zone.

104. A combined typewriting and computing mechanism comprising a travelling carriage, a travelling register having both column and grand totalizers each of which comprises trains of mechanism for setting up numbers therein when the register is in the computing zone, a master wheel for actuating said trains of gearing, and means cooperating with the trains of the column totalizer as the master wheel cooperates with the grand totalizer to prevent setting up any number in the grand totalizer except the total in the column totalizer.

105. A combined typewriting and computing mechanism comprising a travelling carriage, a travelling register having both column and grand totalizers each of which comprises trains of mechanism for setting up numbers therein when the register is in the computing zone, a master wheel for actuating said trains of gearing, and means cooperating with the trains of the column totalizer as the master wheel cooperates with the grand totalizer to prevent setting up any number in the grand totalizer except the total in the column totalizer, said means being automatically rendered effective by movement of the grand totalizer into the computing zone.

106. A combined typewriting and comput-

- ing mechanism comprising a travelling carriage, a travelling register having both column and grand totalizers each of which comprises trains of mechanism for setting up numbers therein when the register is in the computing zone, a master wheel for actuating said trains of gearing, and means cooperating with the trains of the column totalizer as the master wheel cooperates with the grand totalizer to prevent setting up any number in the grand totalizer except the total in the column totalizer, said means being automatically rendered effective by movement of the grand totalizer into the computing zone, and rendered again ineffective by the return movement of the carriage.
107. A combined typewriting and computing mechanism comprising a column totalizer, a grand totalizer, each totalizer having trains of mechanism for setting up numbers therein when it is in the computing zone, a master wheel, and an error check member, the error check member cooperating with corresponding denominations in the column totalizer as the master wheel engages in the grand totalizer, and preventing the setting up of an incorrect total in the grand totalizer.
108. A combined typewriting and computing mechanism comprising a travelling register having column and grand totalizers, key operated means for entering numbers in either totalizer when it is in the computing zone, a series of members which normally permit complete operation of any desired numeral key, and means automatically rendered effective by the movement of the register to bring the grand totalizer into the computing zone to prevent complete operation of an incorrect key at this time.
109. A combined typewriting and computing mechanism comprising a travelling register having column and grand totalizers, key operated means for entering numbers in either totalizer when it is in the computing zone, a series of members which normally permit complete operation of any desired numeral key, a series of auxiliary gears in the column totalizer, and means automatically rendered effective by the movement of the register to bring the grand totalizer into the computing zone and controlled by said auxiliary gears to prevent complete operation of an incorrect key at this time.
110. A combined typewriting and computing mechanism comprising a travelling register having column and grand totalizers, key operated means for entering numbers in either totalizer when it is in the computing zone, a series of members which normally permit complete operation of any desired numeral key, means automatically rendered effective by the movement of the register to bring the grand totalizer into the computing zone to prevent complete operation of an incorrect key at this time.

an incorrect key at this time, and mechanism for automatically rendering said means again ineffective.

111. A combined typewriting and computing mechanism comprising a travelling register having column and grand totalizers, key operated means for entering numbers in either totalizer when it is in the computing zone, a series of members which normally permit complete operation of any desired numeral key, a series of auxiliary gears in the column totalizer, means automatically rendered effective by the movement of the register to bring the grand totalizer into the computing zone and controlled by said auxiliary gears to prevent complete operation of an incorrect key at this time, and mechanism for automatically rendering said means again ineffective.

112. A combined typewriting and computing mechanism comprising a travelling register having column and grand totalizers, key operated means for entering numbers in either totalizer when it is in the computing zone, a series of members which normally permit complete depression of any desired numeral key, and means automatically rendered effective by the movement of the register to bring the grand totalizer into the computing zone to prevent complete depression of an incorrect key at this time.

113. A combined typewriting and computing mechanism comprising a travelling register having column and grand totalizers, key operated means for entering numbers in either totalizer when it is in the computing zone, a series of members which normally permit complete depression of any desired numeral key, a series of auxiliary gears in the column totalizer, and means automatically rendered effective by the movement of the register to bring the grand totalizer into the computing zone and controlled by said auxiliary gears to prevent complete depression of an incorrect key at this time.

114. A combined typewriting and computing mechanism comprising a travelling register having column and grand totalizers, key operated means for entering numbers in either totalizer when it is in the computing zone, a series of members which normally permit complete depression of any desired numeral key, means automatically rendered effective by the movement of the register to bring the grand totalizer into the computing zone to prevent complete depression of an incorrect key at this time, and mechanism for automatically rendering said means again ineffective.

115. A combined typewriting and computing mechanism comprising a travelling register having column and grand totalizers, key operated means for entering numbers in either totalizer when it is in the comput-

- ing zone, a series of members which normally permit complete depression of any desired numeral key, a series of auxiliary gears in the column totalizer, means automatically rendered effective by the movement of the register to bring the grand totalizer into the computing zone and controlled by said auxiliary gears to prevent complete depression of an incorrect key at this time, and mechanism for automatically rendering said means again ineffective.
116. A computing mechanism comprising a travelling register having column and grand totalizers, and error check means controlled in its operation solely by the condition of the column totalizer and checking the entry of a number digit by digit in the grand totalizer when the latter is in the computing zone.
117. A computing mechanism comprising a travelling register having column and grand totalizers, and error check mechanism for the grand totalizer brought into effective condition by the movement of the register to bring the grand totalizer into the computing zone, said error check mechanism being controlled in its operation solely by the condition of the column totalizer.
118. A computing mechanism comprising a travelling register having column and grand totalizers, and error check mechanism controlled in its operation step by step by the condition of the column totalizer but resulting in no change in the condition thereof.
119. A computing mechanism comprising a travelling register having column and grand totalizers, and error check mechanism rendered effective by the movement of the register to bring the grand totalizer into the computing zone, said error check mechanism being controlled in its operation by the condition of the column totalizer but causing no change in said condition.
120. A computing mechanism comprising a travelling register having column and grand totalizers and error check mechanism for the grand totalizer rendered effective solely by the travelling movement of the register to a predetermined position and controlled solely by the condition of the column totalizer.
121. A computing mechanism comprising a travelling register having column and
- grand totalizers, and error check mechanism 55 automatically rendered effective by the travelling movement of the register to a predetermined point and controlled in its operation solely by the condition of the column totalizer but causing no change in said condition.
122. A computing mechanism comprising a travelling register having column and grand totalizers, and error check mechanism brought into effective condition by the movement of the grand totalizer into the computing zone, said error check mechanism being controlled solely by the condition of the column totalizer and operating to check the entry of the total into the grand totalizer 70 digit by digit.
123. A computing mechanism comprising a travelling register having column and grand totalizers, and error check mechanism controlled solely by the condition of the column totalizer for checking the entry of a total into the grand totalizer digit by digit but causing no change in the condition of the column totalizer.
124. A computing mechanism comprising a travelling register having column and grand totalizers, and error check mechanism rendered effective solely by the movement of the register to a predetermined position and controlled solely by the condition of the column totalizer for checking the entry of a total into the grand totalizer digit by digit but causing no change in the condition of the column totalizer.
125. A computing mechanism comprising a travelling register having two totalizers and means operative when one totalizer is in the computing zone but controlled by the condition of the other totalizer for checking the writing of the total appearing in said other totalizer.
126. A computing mechanism comprising a travelling register having two totalizers and means automatically rendered effective by the movement of one totalizer into the computing zone but controlled solely by the condition of the other totalizer for checking the writing of the total appearing in said other totalizer but without causing any change in the condition thereof.

In testimony whereof, I have hereunto
subscribed my name.

GUSTAVE O. DEGENER.
